UNITED STATES PATENT OFFICE.

GEORGE E. CURTISS, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A CASE FOR VACUUM-JUGS.

48,439.

Specification for Design.

Patented Jan. 11, 1916.

Application filed January 14, 1915. Serial No. 2,287. Term of patent 14 years.

To all whom it may concern:

Be it known that I, GEORGE E. CURTISS, a citizen of the United States, and a resident of New Britain, in the county of Hartford, State of Connecticut, have invented a new, original, and ornamental Design for a Case for Vacuum-Jugs, of which the following is a specification, reference being had to the accompanying drawing, forming part hereof.

The figure is a side elevation of a case for vacuum jugs illustrating my new design.

I claim:

The ornamental design for a case for vacuum jugs, as shown.

GEORGE E. CURTISS.

Witnesses:

LOUISE P. ALBRECHT,
JOHN A. LINDSAY.
